UNITED STATES PATENT OFFICE.

BERTRAND G. JAMIESON, OF BROOKFIELD, ILLINOIS.

ELECTRIC-SWITCH-HOUSE CONSTRUCTION.

Application filed April 8, 1922. Serial No. 550,927.

To all whom it may concern:

Be it known that I, BERTRAND G. JAMIESON, a citizen of the United States, residing at Brookfield, in the county of Cook and State of Illinois, have invented a certain new and useful Improvement in Electric-Switch-House Construction, of which the following is a full, clear, concise, and exact description, reference being had to the accompanying drawings, forming a part of this specification.

My invention relates to electrical distribution systems and more particularly to switch house and bus arrangement.

It is known that the extent of distribution of electrical energy can be increased if an increase in the voltage of transmission is permissible. The greater the extent of distribution, the greater is the tendency towards concentration of power in the central station which serves such extended districts. Greater economy is obtained by concentration of generating capacity, and the tendency is constantly to greater centralization of energy generation.

The increase in voltage and the greater concentration of power in each station raise a danger of very considerable magnitude. This is further augmented where a number of power stations are tied together in an interconnected system.

In no other part of the central station is there so great a concentration of power as on the bus system of the switch house. In a large central generating station the vast amounts of energy that are pouring through the busses is almost beyond conception. If this energy should get beyond control, the possibilities for damage are great. The greater extent of distribution, the more important it is to avoid interruption of service because of the great number of customers affected. A high factor of safety at this point is always desirable. The greater the concentration, the higher should be the factor of safety, because of the greater increase in potential damage. Hence, in the switch house, a method of construction and arrangement which will provide a greater factor of safety than mere increase in size and thickness of insulation, is desirable.

In devising a suitable construction, two types of possible damage are to be taken into account. The first is the possibility of phase to ground short circuit, and the second is the possibility of interphase short circuit.

A disturbance of the first type, namely, from a bus phase to ground, can be limited by a suitable resistance inserted in the generator neutral to ground connection, but an interphase bus short circuit has possibilities for terrific damage and a widespread interruption of service. It is, therefore, of greatest importance to furnish means for raising the factor of safety.

The object of my invention is to provide an arrangement and spacing of the parts of an electrical switching system and switch house, which will insure a higher factor of safety at a reasonable cost, and within a space, not substantially in excess of, and in some cases less than, the space required by prior art constructions.

My invention further aims to provide a system of switching which requires less men to operate, and which provides a greater degree of safety than systems of the prior art. In order to acquaint those skilled in the art with the manner of construction and operating a system embodying my invention, I shall now describe, in connection with the accompanying drawings a simplified form of the invention.

In the drawings:

Figure 1 is a transverse vertical section through a simplified form of switch house embodying my invention;

Fig. 2 (on two sheets—part 1 and part 2) is a transverse section taken on line 2—2 of Fig. 3 showing a switch house embodying my invention.

Fig. 3 is a longitudinal section taken on line 3—3 of Fig. 2:

Fig. 4 (on two sheets—part 1 and part 2) is a horizontal sectional view taken on different floors on the stepped line 4—4 of Fig. 2:

Fig. 5 is a diagram of connections shown on two sheets (part 1 and part 2):

Fig. 6 (on two sheets part 1 and part 2) is an elevational view of a part of a switch

house construction built according to my invention. This is an elevation looking north;

Fig. 7 is a horizontal section taken on line 5 7—7 of Fig. 6, part 1;

Fig. 7^a is a similar view taken on line 7^a—7^a of Fig. 6, part 2;

Fig. 8 is a horizontal section on line 8—8 of Fig. 6, part 2;

Fig. 8^a is a similar view on line 8^a—8^a of Fig. 6, part 1;

Fig. 10 is a vertical section taken on 15 line 10—10 of Fig. 6, part 1;

Fig. 11 is a similar view on line 11—11 of Fig. 6, part 2;

Fig. 12 is a similar view taken on line 12—12 of Fig. 6, part 2;

Fig. 13 (on two sheets part 1 and part 2) 20 is an elevational view of a part of the switch house construction taken on the opposite side of the dividing wall with respect to the elevation of Fig. 6. This is an elevation looking south;

Fig. 14 is a horizontal section taken on line 14—14 on Fig. 13, part 1;

Fig. 14^a is a similar view taken on line 14^a—14^a on Fig. 13, part 2;

Fig. 15 is a horizontal section taken on 30 line 15—15 on Fig. 13, part 1;

Fig. 15^a is a similar view taken on line 15^a—15^a on Fig. 13, part 2;

Fig. 16 is a fragmentary horizontal section 35 taken on line 16—16 of Fig. 13, parts 1 and 2;

Fig. 17 is a vertical section taken on line 17—17 of Fig. 13, part 1;

Fig. 18 is a similar view taken on line 40 18—18 of Fig. 13, part 2;

Fig. 19 is a similar view taken on line 19—19 on Fig. 12, part 2;

Fig. 20 (on two sheets part 1 and part 2) 45 is a diagrammatic elevational view of the overhead operating mechanism and its relation to the switch and disconnect mechanism;

Fig. 21 (in two parts on the same sheet) 50 is a plan view of the overhead switch operating mechanism; and

Fig. 22 (in two parts on the same sheet) 55 is a floor plan of the upper floor (operating mechanism floor) showing the layout for locating the operating mechanisms and for transmitting motion down to the circuit breakers and disconnect switches.

In Fig. 1 I have shown a simplified or more or less diagrammatic form of my invention.

It will be noted that the illustration and description herein relate to three phase systems. The invention is equally applicable to any other number of phases and the invention is to be so considered except as to 65 such claims as are specifically limited to

three phase systems. The construction shown is divided horizontally into four floors or levels. The lowermost floor or level which is preferably below grade is the cable floor 1 which provides room for incoming and outgoing cables and the pot heads for taking out the individual conductors to their separate compartments from the cable. This floor is preferably below grade on substantially the level of the incoming cable ducts. 70

The next higher floor or level 2 is devoted to the housing of the reactors 8, 9 and 10 which are inductive safety devices in series in the line phase conductors 5, 6, 7 leading to or from the main busses 14, 15 and 80 16. The next higher floor above the reactor floor 2 is the oil switch floor 3 which is devoted to the oil switches 11, 12 and 13 and the main busses 14, 15 and 16. The uppermost floor 4 is devoted to the switch operating mechanism. This mechanism comprises a power operated member 17 (the details of which I have not herein illustrated) connected by rods 18 to motion transmitting means 19, 20 and 21 which are connected to operating 90 rods 22, 23 and 24 for the oil switches 11, 12 and 13.

The mechanism floor provides a room extending completely across the width of the structure providing an unobstructed view 95 of all of the mechanisms for operating the various switches, etc. The three lower floors are divided vertically by partitions 26 and 27, which run vertically between the floor of the mechanism room and the floor 100 of the cable room between the outer walls 25, 28. In this manner the structure is subdivided into three longitudinally extending galleries for each floor level. The oil switches of each gallery are separated from each other by vertical partitions 33 made of concrete, brick, asbestos or the like, and the reactors 8, 9 and 10 are similarly separated from each other in each gallery by vertical partitions of insulating material of the same character as the partitions 33 on the upper floor. Current transformers 35, 36 and 37 are housed above the reactor devices 8, 9 and 10 between the partitions 34 above referred to. The main busses 14, 15 and 16 115 are mounted in longitudinal bus compartments formed by the adjacent walls 38, 39 and 40 and the adjacent partitions or walls 26, 27 and 28 as well as the floor 29 of the mechanism room. The conductors 5, 6 and 120 7 enter the cables through suitable pot heads on the cable floor. These potheads also lie in separate compartments on the cable floor formed by partitions 34.

It will be noted from the above that each 125 floor contains mechanism of the same character throughout. Each floor is divided into galleries, all the apparatus of each gallery being devoted to one phase. Thus, all the apparatus in the left hand tier of 130

rooms or galleries is devoted to phase A, all of the rooms or galleries in the middle tier are devoted to apparatus relating to phase B, and similarly all the rooms or galleries 5 in the right hand tier are devoted to apparatus for the phase C. The phases are segregated a maximum distance within the limits of the space devoted to the construction. This spacing is always great enough 10 to permit an attendant to work freely in the space between phases. A high factor of safety is secured, since the conductors of different phases are spaced apart a maximum distance, and the apparatus on each 15 floor or gallery is so arranged and enclosed that a workman cannot make an accidental connection between phases. All of the apparatus in the same room or gallery is of the same phase, and of the same potential. 20 This means much greater safety than has heretofore been possible.

A single mechanism for operating the separate pole or phase elements 11, 12 and 13 is connected through the rod 18 to the 25 vertical operating rods for performing a common mechanical operation, namely, that of separating the oil switch contacts. The apparatus on the mechanism floor 4, is however, not live, that is, it is not electrically 30 connected to any high-tension conductor, and consequently, no danger to the attendants is encountered. It is possible to see from any position on the floor 4 just what the condition of the corresponding apparatus is. Thus an attendant or operator has 35 a comprehension of the situation which it is not possible to obtain from apparatus of the prior art. I have shown no disconnecting switches in this structure, since the present showing is largely diagrammatic, but these 40 may be placed at suitable points as desired. The conductors 5, 6, 7 may be taken as outgoing or line conductors, and the switches 11, 12 and 13 are therefore line switches. 45 The incoming cable from the generator may enter in substantially the same manner, namely, by way of cables in on the cable floor and leading up through the respective reactors current transformers generator oil 50 switches to the main bus bars 14, 15 and 16. The invention is not limited to parallel dis- 55 position of the walls 26-27 and 28. They may be superposed if desired, so that the oil switches and reactors of the different phases may be installed in galleries one above the other. In that event the switches 60 may be operated from a common vertical operating rod instead of the cross rods 18. These vertical rods may be extended through the walls in a manner indicated hereafter.

I shall now describe in connection with Figs. 2, 3, 4 and 5, an embodiment of my invention which appears at present at the 65 Calumet station of the Commonwealth Edi-

son Company of Chicago. In this description and this illustration, I have omitted as many of the details as possible, to bring out more clearly the fundamental novelty involved. In Figs. 6 to 22 I have shown in 70 detail the actual construction employed in the Calumet station.

Referring more specifically to Fig. 2 which is shown on two sheets as part 1 and part 2, it will be seen that instead of having 75 a single set of conductors and apparatus as shown in Fig. 1, I have provided the conductors and apparatus in duplicate grouping the same about the partitions 26, 27 and 28 with the apparatus of each phase arranged in duplicate back to back. The switch house in this construction is identical so far as the number of floors are concerned, namely, the cable floor 1 the reactor floor 2, the oil switch floor 3 and the mechanism floor 4. However, the galleries are double 80 in number the galleries shown in Fig. 1. In addition to the partitions 26, 27 and 28, I have provided separating walls 41, 42, 43 and 44 which thus provide the additional 85 galleries required for the duplicate apparatus. The line busses 14 and 14* being arranged on opposite sides of the partition 26 are of the same phase and consequently 90 of substantially the same potential, and they 95 may therefore be placed as close together as the supporting strength of the concrete wall 26 will permit. These line busses are connected through disconnect switches 45 and 45* through downwardly extending conductors 48 and 48* to the stationary contacts 51 and 51* which cooperate with the contact on the oil switches 11 and 11*. The oil 100 switches are preferably of the movable or truck type so that they may be wheeled out of the particular cells in which they are placed for repairs or replacement. The oil 105 switches 11 are then connected to the current transformers 35, 35* and from thence to the reactors 8 and 8*. 110

The reactors are in turn connected through the disconnect switches 54 and 54*, to the conductors 5 and 5* which lead into the cables 59 and 60 through the pot heads 57 and 58.

The apparatus on each side of the wall 26 is duplicated at the walls 27 and 28.

In addition, it will be noted on the wall 28 that the two potential transformers 61 and 61* which are connected to lines 59 and 120 60 respectively, are mounted on opposite sides of this wall in the cable room or cable floor 1.

In Figure 4, I have shown the main busses 66 and 66* on opposite sides of the wall 27. 125 These busses extend the full length of the station as will be apparent from the diagram of Figure 5 being partitioned off by horizontal walls 69 and 69*, and back walls 72 and 72*. Thus, a longitudinal channel 130

is formed, this channel being divided into short lengths by the transverse walls forming continuations of the walls such as 34 and 34^x. Suitable bushing type insulators 15 and 15^x are mounted in these transverse walls in order to provide suitable support for the main bus conductor. This manner of mounting the bus conductors is highly meritorious. It provides a support which is inexpensive and easily constructed, but which at the same time is of great strength, rigidity and permanence. These short lengths or cells and in fact all the cells are closed off by suitable covers (not shown). In a similar manner, the line busses 15 and 15^x are supported in channels which are divided into compartments or cells, as is apparent from Fig. 3. The disconnect switches, such as 46^x are also housed in similar cells between the upper walls, such as 39^x, and the lower walls, such as 75^x shown in Fig. 3 and Fig. 2 part 2 and the continuations of the vertical partition 33^x, also shown in Fig. 3. In a similar manner the current transformer 36^x is housed in a cell defined in parts by the upper wall 69^x and the lower wall 78^x and the side walls 34^x. The reactor 9^x is similarly housed in a cell defined by the upper wall 78^x and the floor 31, the side walls being continuations of the walls 34^x. All of these cells are adapted to have suitable covers for closing them.

It will be noted that the outer and intermediate walls 41, 42, 43 and 44 in Fig. 2 are indicated by cross section different from that of the main walls 26, 27 and 28. This is because these walls 41, 42, 43 and 44 may be omitted to make an outdoor station with considerable wider separation of phases. It will be understood that in the preferred form of my invention concrete walls and floors are employed because of their current limiting characteristics, but while such construction is preferable, it is not essential. These walls 41, 42, 43 and 44 and adjacent portions of the intermediate floor 30, may be removed to form an open or outdoor switch house. The maximum spacing of phases is employed whether the intermediate walls are present or not.

In Fig. 4 part 1 I have shown one bay which is devoted to outgoing transmission lines V, VI, VII and VIII, which lines have their B phase conductors connected to line bus 15^x. This will be clear by consulting the diagram of Fig. 5, part 1.

The generator 80 is connected through the three reactors 81, 82 and 83 to the conductors 84, 85 and 86 which are preferably cabled to the switch house where these conductors connect directly to the main busses and indirectly to the line busses as follows:

Conductor 84 being devoted to phase A is connected through oil switches 87 and 87^x to

the main busses 65 and 65^x for the A phase. 65 This conductor 84 is also connected indirectly through the oil switches 90 and 90^x to the line busses 14 and 14^x.

Figure 5, part 2, refers to bays No. 1 and 2 of the Calumet sub-station in which there 70 is an arrangement to take off power for an auxiliary power bus and to a 33,000 volt transformer, which does not occur in bays 3 and 4. The elevational view of Fig. 3 refers to bay No. 3. Lines I to IV are connected to 75 the line bus 14 through the line switches or circuit breakers 99, 96, 11 and 93, respectively, these switches being of 600 ampere current carrying capacity in the present construction. The circuit breakers 90 and 102 80 which tie the line bus 14 into the main busses 65 and 65^x and the circuit breakers which tie the main busses to the generator are each in this case of 2,000 ampere current 85 carrying capacity.

In a similar manner, the lines V to VIII are connected through circuit breakers 99^x, 96^x, 11^x and 93^x, respectively, to the line bus 14^x which can be selectively fed from either bus No. 1 or from bus No. 2 of phase A. 90 The other phases are similarly connected. These circuit breakers are rated at 600 ampere current carrying capacity. The line bus 14^x is tied to the main bus 65^x through circuit breaker 90^x which is of 2,000 ampere 95 carrying capacity. In a similar manner, the generator lead 84 is connected to bus 65^x through the circuit breaker 87^x which is rated at 2,000 ampere carrying capacity.

It will be noted that the outgoing lines are 100 all connected through reactors for limiting the current flow. These reactors are current flow limiting devices. In a power station such as this, the bus is considered as the fountain head of power for the various lines supplied by it. The pressure on this bus system must be maintained above a certain value. These reactors have a value such that with a given generator capacity connected 105 to the bus and with a fault occurring immediately beyond the reactors the current value will be limited to a prescribed value which can be supplied by the generators while maintaining the normal voltage of the 110 bus. For a fault to ground, the reactors 81, 82 and 83 (see Fig. 5) are not so effective since only a single one is in series with the fault, but the grounded neutral contains a resistance 105 which may be relatively high 115 so that the flow of current on a fault to ground may be restricted to a value which is not dangerous.

Each of the auxiliary busses 14 and 14^x in phase A may be tied to the opposite main bus 65 or 65^x, as the case may be, through the circuit breakers such as 102 and 103^x. The circuit breakers for these bus ties are each 125 made of a carrying capacity of the order of

2,000 amperes, since the entire power for the four outgoing lines may be carried in series therethrough.

The switchhouse is the place where all of the connections come together in most intimate relation, but in the present construction, I have secured a very high factor of safety, first by the remote or segregated phase arrangement, and second by the liberal use of reactors. As to the remote phase arrangement it will be noted that the bus bars and connections thereto of the different phases are as far separated as is possible and are maintained in separate galleries, so that an accidental short circuit between phases is, so nearly as I can foresee, impossible.

The outgoing lines are all provided with reactors in series, these reactors being of such a characteristic that they will limit the current flow to safe values for the operation of the cooperating circuit breakers and tend to maintain normal potential on the busses as far as possible.

The switch operating mechanism is also made of a noteworthy characteristic, namely, that these breakers are disposed in remote relation with respect to each other just as are the phase conductors and an overhead operating rod reaches across the three phases for operating the corresponding switches of a given line. As previously mentioned, all the apparatus on a given floor is of the same character. Hence, materials for repairs or replacement will not need to be moved from one floor to another and the location of any trouble, if it should occur, would be very readily accomplished because of the scientifically grouped relation of all of the elements of one character in one group, all of the elements of another character in a separate group, etc.

This type of construction is applicable, not only to in-door stations, but also to out-door stations, by the omission of certain walls.

A further feature of safety and novelty is the employment in the case of lines of disconnects above and below the oil circuit breakers, these disconnects being selectively automatically or manually operated within the heavy duty breaker or bus chambers. The generator and group circuit breakers similarly have disconnects on both terminals operable selectively either automatically or manually. As I shall presently illustrate more in detail, I provide automatic disconnecting switches operated by the same mechanisms which opens the oil circuit breakers, so that the opening of the circuit breakers is accompanied by an automatic operation of the disconnects, and an indication of this fact on the upper floor.

Referring to Fig. 4, attention is called to the fact that the cellular construction on

the longitudinal walls 26, 27 and 28 is here well illustrated. The longitudinal wall itself forms a backbone or frame for the cellular construction which projects from each side of the wall. The details corresponding to the third line, such as taken on the section 2-2 of Fig. 4, and as shown in Fig. 2, have been provided with reference numerals and it will be understood that this is illustrative of the general construction. 75

Attention has not heretofore been called to the fact that the lower disconnect switches 54, 55 and 56 and their counterparts 54^x, 55^x and 56^x (see Fig. 2) are all housed in cells formed by the main walls 26, 27 and 28 and partitions extending outwardly therefrom. The wall 26 has the partitions 106 and 106^x extending from the lower floor 31 to the basement floor 32, thus effectively housing the disconnect switches 54 and 54^x. 80 In a similar manner, the wall 27 has the partitions 107 and 107^x. The wall 28 has the partitions 108 and 108^x. The potential transformers such as 61 and 61^x, as shown at the right of Fig. 2, part 2, are also housed 85 in the same cells. This will be apparent from Fig. 4, part 2.

I shall now proceed with a description of the embodiment of my invention as it appears in the Calumet station in Chicago. 95 For this purpose, I am illustrating in Fig. 6 one wall of phase B bay 1 looking north. Fig. 13 is a similar elevational view of the other side of the wall phase B, bay 1 looking south. 100

Referring now more particularly to Fig. 6, parts 1 and 2 and to Fig. 5, part 2, which illustrate bay I, I wish to point out the specific features of construction herein illustrated. Generator No. 1 has a grounded neutral containing a resistance 106 for the purpose as previously described of limiting phase to ground short circuits. This generator which I have designated as 107 is connected through the reactance coils 108, 109 and 110 to the generator leads 111, 112 and 113. Generator lead 111 is devoted to the A phase; lead 112 is devoted to the B phase, and lead 113 is devoted to the C phase. 110 115

In Fig. 6, part 2, the leads 112 and 113 are shown as entering at the righthand or eastern side of the power house in the passageway 115. This passageway 115 is formed on the one side by the east end wall 116, floor 29 upon which the overhead operating mechanism is mounted, the partition 117 and the intermediate floor 30. The generator leads 111, 112 and 113 each consisting of two cables are led in through transverse channels 118 which are separated into compartments by transverse walls 119 which provide supporting insulators. 120 125

Immediately below the upper mechanism floor 29 there is a horizontal row of com- 130

parts which I have shown in Fig. 6 2000 ampere oil circuit breakers designated 65 and designated by reference numerals 120 by reference numerals 167 and 168.

The compartments are formed by the 5 main longitudinal walls which form the vertical backs of the compartment (see Figs. 6, 8 and 12), the wall 127 herein being the wall devoted to the B phase. The other 10 walls of these compartments are formed by a horizontal partition 128 and a series of vertical partitions running between the upper floor 29 and the lower floor 30, these 15 partitions being herein designated by reference numerals 129, 130, 131, 132, 133, 134, 135 and 117. These compartments 120 and 126, inclusive, contain horizontally extending 20 connections which include the line bus 136 and certain other connections relating thereto.

Immediately below the compartments 120 and 126, inclusive, is a series of compartments 137 and 143, inclusive. These compartments contain disconnect switches such as I have indicated by reference numeral 144 in each of the compartments. In compartment 137 and 138 there are two of these disconnect switches. The same is true of compartment 142 and 143. The other compartments have a single disconnect switch, 30 since the switches in the latter compartment are in series with the line conductors leading out to the various lines. These disconnect switch compartments are formed between an upper partition 128 and a lower partition 145 and are spaced off horizontally by the vertical partitions 129 to 117, 35 inclusive. The backs of the partitions are similarly formed by the main vertical longitudinal walls.

Immediately below the disconnect switch compartments are formed a series of oil 40 switch compartments which I have numbered with reference numerals 146 to 152, inclusive.

It will be noted that the two end compartments at the left and one at the right of Fig. 6 for the disconnect switches and for the oil circuit breakers have separate compartments divided off by means of vertical 50 walls 153 and 154 at the left end of the bay and 155 at the right end of the bay. These walls form vertical compartments running down to the floor 30 for the conductors 157 and 158 at the left and the conductor 159 55 at the right connecting to the main busses respectively.

In addition, the intermediate compartments 148, 149 and 150 have vertical compartments divided off by walls 160, 161 and 60 162 for leading down the conductors 163, 164 and 165 to the horizontal wall 30 for connection to reaction and current transformers.

The compartment 146 and 147 contain

2000 ampere oil circuit breakers designated 65 by reference numerals 167 and 168.

The three intermediate compartments 148, 149 and 150 contain 600 ampere oil circuit breakers designated by reference numerals 169, 170 and 171. The right hand 70 compartments 151 and 152 contain the 2000 ampere oil circuit breakers 172 and 173.

These oil circuit breakers are provided with vertical operating rods indicated by reference numerals 175 and 181, inclusive. 75 These rods are shown in section in Figs. 7 and 7^A. The rods are passed through the upper compartment enclosed in tubes numbered respectively 179 to 185, inclusive. Where these tubes or ducts lie between vertically disposed conductors as in the two end compartments at each end of the bay, a concrete wall extends between the conductors and includes the conduit or pipe to serve also as division wall between a dead 80 and live conductor and to facilitate cleaning and inspection.

These conductors are pipes through which the rods for operating the oil circuit breakers project are preferably formed of a non- 90 conducting fibrous material.

The partitions are preferably formed of asbestos or a composition made of asbestos and Portland cement, or the like.

These operating rods for the oil circuit 95 breakers are arranged to be operated by overhead actuating mechanism which will be described more in detail later.

The operating mechanism which is on the uppermost floor is also arranged to actuate 100 the disconnect as will be described more in detail later.

Between the intermediate floor 30 and the lower floor 31 I have provided a longitudinal passageway for the main bus 186 which 105 in this case is bus No. 2 of the B phase. This bus being a continuation of the bus marked 66^A in part 1 of Fig. 5. The bus is enclosed between the ceiling of the upper floor 30 and a longitudinally extending 110 horizontal wall 187 which has suitable transverse walls, such as shown at 188, for mounting the supporting insulators 189. In this connection it is to be noted that wherever a conductor of 115 this character, that is to say, of any potential or carrying capacity passes through the walls or partitions, suitable insulators are provided at the intersection of the walls or partitions with said conductor. The 120 longitudinal housing for the main bus has the back wall 190 so that a continuous housing for the bus is formed close to the forward edges of the partitions 191 to 196, inclusive. Partly back of and partly below the longitudinal main bus compartment are provided a series of transformer compartments 197 to 202, inclusive. The compart-

ments 197 to 200 contain current transformers and the compartments 201 and 202 contain potential transformers connected to main bus and generator lead.

5 Immediately below the transformer compartments are the reactor compartments 203 to 206, inclusive, with an additional vacant compartment 207 at the right end of the bay. The compartment 203 is made relatively larger than the compartments 204, 205 and 206 because it contains a reactor of greater current carrying capacity than the others. The reactor 209 is adapted for a continuous current flow of 800 amperes, whereas the reactors 210, 211 and 212 are adapted to continuous current flow of 300 to 450 amperes.

20 The reactor 209 in turn is connected through a conductor 215 to a 15,000 k. v. a. transformer raising the voltage from 12,000 volts to 33,000 volts. This transformer or bank of transformers is designed particularly for transmission of power to a remote point. In fact, this may serve as the tie between the present station and other stations. The conductor 215 is preferably cabled out of the switch house. The reactors 210, 211 and 212 are connected in series with cable connections 216, 217 and 218 to disconnect switches and then taken out through the cables 219, 220 and 221. These cables begin or terminate with the end bells 222, 223 and 224 and are located in the compartments 226, 227 and 228, respectively, in the basement below the floor 31.

25 These compartments and the compartment 225 may contain potential transformers 230, 231, 232 and 233.

30 The lines 216, 217 and 218 before they enter the cables 219, 220 and 221 are led through disconnecting switches 234, 235 and 236, respectively, as above stated.

35 It will be understood that the three phases are identical but that the end bells are located on B phase wall and that the conductors 216, 217 and 218 from the end bells 222, 223 and 224 are connected with conductors of the other phases, as is well understood by those skilled in the art.

40 Attention is called to Fig. 5, part 2, to the fact that there is a connection 238 running from the main bus 186 through the wall 127 to a circuit breaker on the opposite side. This permits a line bus to be connected to either main bus 1 or 2. This is shown in Fig. 10 on the same level as the conductor 158 where it passes through the wall 127. The conductor is also shown in plan view on Fig. 8.

45 The conductor 159 which is connected between the oil circuit breakers 172 and 173 and the main bus 186 is shown partly in Fig. 6, part 2, and shown in plan in Fig. 8A.

50 Now stepping to the other side of the wall 127 and looking south at bay 1, phase B

(the opposite side of the wall just previously described) the counterpart of the apparatus just previously described, will be seen. The end wall 116 which previously appeared on the right hand side, now appears on the left hand side.

55 I have designated the parts which are exact counterparts of those previously described by primed reference numerals. Where the same parts appear either in part 75 or in whole in both views they have the same reference numerals.

In this connection, attention is called to the connection 214 which runs from the connection from the tie conductor 240 between the oil switches 167' and 168' in order to provide for only one riser from the main bus 2 (see the top of Fig. 13, part 2, and the diagram of connection, Fig. 5, part 2). This conductor 214 runs diagonally through the 85 longitudinal vertical wall 127 (see Fig. 7 and see also Fig. 14A).

60 Attention is called to the fact that since the oil circuit breakers are connected at the back, all in standard fashion, these circuit breakers being of the portable type and adapted to be wheeled out of the compartment for replacement or repair, the terminals which in Fig. 6 appeared at the right will now appear at the left, and vice versa. 95 This is done in order to offset the operating mechanism and to provide space for same. Thus, for instance, referring to Fig. 13, part 2, the oil circuit breaker shown at 167' has its conductor 157' at the right instead of at 100 the left in the corresponding switch in Fig. 6.

65 The conductor 159' which ties the bus 186' to the tie conductor 241' between switches 172' and 173' is in Fig. 13, part 1, led down 105 in the compartment containing the switch 173' on this side of the wall instead of being led down in the adjacent compartment as it is in the other side of the wall, shown in Fig. 6, part 2.

70 Except for the above mentioned differences and other minor and unimportant differences, the two sides of the wall have the same symmetrical connections and contain the same units and apparatus.

75 Bay No. II is made up in substantially the same manner as bay No. I. In this case, however, the generator leads from generator No. 1, which are connectible by the oil switches such as 173 and 173' to the main 120 busses, such as 186 and 186' for the B phase, and which are connectible indirectly to the line busses 136 and 136' for the phase in bay I, need not be connected in bay II.

80 However, there is a bus tie shown at 259 in 125 B phase, bay II, (see Fig. 5, part 2) which is adapted to connect together the leads 251 and 252, which leads run off to a 12,000 volt auxiliary power bus, which bus supplies the current for the auxiliary apparatus in the 130

power station. The oil circuit breakers 253 and 254 are connected in series with the lines 251 and 252, respectively, these breakers being of a carrying capacity of 2,000 amperes. The oil circuit breaker 255 which is connected in the bus tie 250 is also of a carrying capacity of substantially 2,000 amperes.

The lines 251 and 252 have in series there-
10 with the reactors 256 and 257 adapted to a continuous flow of current to substantially 1,000 amperes. The oil circuit breakers 253 and 254 are connected through the leads 258 and 259 to bus 1 and bus 2 of the B phase.

15 The line busses 260 and 261 in bay II, B phase, are connected to the main busses 1 and 2 of the B phase by oil circuit breakers 262 and 263 which are of a carrying capacity at substantially 2,000 amperes. The line 20 switches connected to these line busses are of a carrying capacity of substantially 600 amperes, as previously described in connection with bay I.

In the present switch house each line bus 25 is fed directly from the main bus and not from any particular generator. The main bus extends through the full length of the switch house and is not sectionalized as is the previous practice. This is an important 30 feature of the invention.

The connection to the 12,000 volt auxiliary power busses 264, which appear at the top of Fig. 5, part 2, is indicated for phase A, but the connections for phases B and C have 35 been omitted for the sake of clearness.

Turning now to the overhead operating mechanism I wish to describe briefly and in general terms the mechanism which actuates the oil circuit breakers and the disconnect switches. The particular construction of the operating mechanism of the oil circuit breakers and of the disconnect switches is not disclosed in detail in the present case since the particular construction of these 40 elements, except as herein stated and claimed, may be varied without departing from the present invention. The operating mechanism will be described in detail in a later application. Referring now to Figs. 20, 21 and 22, I shall describe the manner of operation of the overhead mechanism and the operating connections for the circuit breakers and the disconnects and show the relation of the same to the separated phase arrangement so as to bring out the novel relation of these parts and the advantage which resides in the same.

Fig. 20, parts 1 and 2, is a phantom cross-sectional view showing only the main operating parts in outline, since it is believed that this will clarify the disclosure.

This overhead operating mechanism has been indicated in general terms in Figs. 1 and 2.

65 Assume that a transverse section has been

taken on substantially the line 18-18 completely across the switchhouse looking toward the east, that is, in the direction of the arrows as indicated on the section line 18-18 Fig. 13, part 2.

Fig. 20 represents this view.

The overhead mechanism comprises a motor mechanism 270 for the switches of a single line in this case the motor and spring mechanism is placed adjacent the north wall 75 of the building. This motor and spring mechanism has the following characteristics, namely, that it comprises an electric motor or other power supply primarily furnishing the power which compresses certain springs 80 in which sufficient energy is stored to make a complete cycle of operations of the oil circuit breaker and the disconnects before the electric motor needs to be operated to store energy in the springs. A further feature 85 of operation resides in the construction of the disconnect mechanism which is automatically actuated in connection with the oil circuit breakers, which permits the disconnect to be operated separately after the oil 90 circuit breaker is opened, but which prevents operation of the disconnect when the oil circuit breaker is in closed position. This apparatus is not, however, claimed herein.

The motor mechanism has an operating 95 rod 274 made up in a plurality of sections and connected at points 275, 276 and 277 by the operating links there shown, to the parallel motion mechanisms 278, 279 and 280. This parallel motion operating mechanism is 100 devoted to the mechanism in connection with bus No. 2 of phases A, B and C.

The switch operating rod for the A-phase is shown at 282, this switch being connected to the parallel motion mechanism 278 105 shown at the upper left part of Fig. 20, part 1.

Referring to Fig. 22 in which I have shown a plan of the upper floor with the openings therethrough for the operating 110 rods and the disconnect operating rods, the opening 283 formed by a piece of conduit extending downwardly about the operating rod 282 is shown as being placed below the parallel motion mechanism 278. The connected circuit breaker operating rods 284 and 285 for bus No. 2 on phases B and C are 115 not shown although it will be understood that they are similar to the operating rod 282 shown on the A phase. They pass 120 through tubes 286 and 287 as is indicated on Fig. 22.

The connecting rods 274 are formed in sections, as will be apparent from the drawings.

125 At the bases of the parallel motion mechanisms 278, 279 and 280 there are arranged cross rocker shafts 288, 289 and 290 which have attached to them at one side crank arms 291, 292 and 293 to which are connect-

ed vertical operating rods 294, 295 and 296 for operating the disconnects upon both sides of the oil circuit breakers.

As shown at the A phase, the disconnect 5 297 and 298 are arranged above and below the oil circuit breaker 299, respectively. This is because the oil circuit breaker 299 is in this case a line circuit breaker of 600 amperes capacity where the line conductors lead from 10 the line bus at the upper part of the structure down to the switch and from the switch through the reactor to the lower disconnect.

In the larger circuit breakers of 2,000 15 amperes capacity in which the leads run down to the oil circuit breaker and from the oil circuit breaker up again the disconnects are arranged in separate compartments on substantially the same level. The operating rods in this case extend side by side only to the compartment above the oil circuit breakers.

These operating rods for the disconnects extend through tubes embedded in the concrete walls such as the wall 271, and immediately adjacent each one of the operating rods is a tube, such as shown in the plan view of Fig. 22 at 300, 301 and 302, for a grounding cable, these grounding cables being connected to the grounding contacts 303 and 304 of the disconnects. The main operating rods may also be embedded in the walls, but in the present construction it is simpler to extend them directly down to the top of 35 the oil switch, without any intervening operating mechanism. The disconnect has a swinging blade, the stationary end of which can connect with the terminal of the oil circuit breaker and the movable end of 40 which can be connected either to the bus or can be connected to the grounding contacts, such as 303 or 304, for positively rendering the contacts of the oil circuit breaker dead and safe.

45 The bases of the disconnecting switches are set into the concrete wall so that the operating rods may be readily connected and so that the grounding cables may be easily attached to the grounding contacts. Where 50 the disconnects are arranged above and below the oil circuit breakers, they are preferably arranged directly in line so that they may be operated by one common rod. Where the disconnect for the oil circuit breakers 55 are arranged side by side in the upper compartment, two separate operating rods are provided. The plan view shown in Fig. 22 shows the additional tubes for the operating rods and the grounding cables at 305 and 306 on phase A, bus 2. In a similar manner 60 I have indicated the additional tube for the operating rod and the grounding cable at 307 and 308, phase B, bus 2, and at 309 and 310 at phase B, bus 2.

65 The operating rod for bus 2 on phases A,

B and C are connected together by a common transverse operating member, in this construction a rod or pipe 311, which is connected to the operating arms 312, 313 and 314 attached to the cross shaft 288, 289 and 70 290, respectively. This transverse operating rod is arranged in sections as shown on the drawings, each section being supported by swinging arms such as shown at 315, 316 and 317 in connection with the corresponding 75 transverse operating rod which operates the parallel motion mechanisms for the oil circuit breakers in order to prevent bending of the rods.

The motor mechanism which provides the 80 power for operating the circuit breakers and the disconnects, operates the circuit breakers through the rod 274 and the mechanisms 278, 279 and 280. The operating rod for the disconnective switches is not connected 85 to the operating rod for the oil circuit breaker. The parts are so arranged that the oil circuit breaker first breaks the circuit and after certain intervals the disconnects open. After the disconnect switches 90 are opened the movable contacts, which are connected to the circuit breaker terminals, may be moved manually into contact with a grounding contact so that the oil circuit breaker will not have any potential there- 95 upon. The grounding contacts are connected in multiple to a cable or other grounding conductor which leads to ground through a normally open grounding. When it is desired to work on a given circuit breaker, 100 the main grounding switch is closed and the disconnects are then thrown to the grounding contacts.

The motor mechanism 271 (see Figs. 20 and 21) has a similar operating rod 318 105 which actuates the parallel motion mechanisms and operating rods for the oil circuit breakers of busses 1 on phases A, B and C. Thus the operating mechanisms for a particular line generator group or the 110 switch are located in a position corresponding to the disposition of the conductors relating to said line generator group or tie switch.

The invention is not to be limited to the 115 side by side arrangement of the phases on the same floor of the switch house, as the advantages of the segregated phase arrangement may be obtained by superposing the 120 phases one above another on successive floors or by other disposition. Hence, the terms horizontal and vertical employed in the claims are not to be considered as limiting, but as explanatory.

125 Whichever way the disposal of the phases may be, there is always maximum space between phases and hence a large factor of safety. There is always free working room at the open sides of the cells. Heretofore 130 the spacing of phases particularly with re-

spect to the switches has been only so great as that demanded by the potential. According to my invention, the spacing is invariably in considerable excess of the striking 5 distance demanded by the potential.

It will be noted that the potential transformers are all contained within the cells assigned to them and they are connected to ground within their cells, only the second 10 aries which are of low potential leading out of the cells.

I believe that the advantages of the construction which I have described and illustrated are sufficiently set forth above to enable 15 those skilled in the art to construct an embodiment of the invention and gain such advantages.

I do not wish to be limited to the precise details and the precise arrangements 20 which I have illustrated, since my invention is obviously entitled to an interpretation which does not depend upon inconsequential details. I am the first to provide 25 remote or segregated phases in bus construction. I believe that I am the first to provide free usable space between the phases of power conductors in a switch house or the like. I believe also, that I am the first to dispose the apparatus in vertical planes, 30 either parallel or superposed extending longitudinally of the switch house leaving free usable space between the planes, each plane defining the location of conductors, switches, reactors and the like.

35 I am also, so far as I know, the first to provide common switch operating mechanism which is disposed transversely above the live conductors in a switch house. I am also the first, so far as I know, to provide 40 a station which is featured by a very high factor of safety and in which there is provided first maximum spacing of the phases, and second, reactors in all of the conductors coming in or leading out with respect to the busses.

45 I believe furthermore, that I am the first to provide a group of oil circuit breakers operated from a common operating mechanism together with separate and conjointly 50 operating disconnect mechanisms for disconnecting the terminals of the oil circuit breakers and for grounding the same.

55 I also consider that I am the first to provide a switch house in which the separate floors all house similar mechanism.

There are other features of novelty some of which are more particularly pointed out and claimed in the following claims:

I claim:

60 1. In a bus structure, a plurality of longitudinally extending walls, a bus having a bus conductor extending along each wall longitudinally thereof, a line comprising a line conductor extending along each wall, 65 said line conductors lying in substantially

a common transverse plane, said walls with their correlated conductors being spaced apart to provide free working room for an attendant between said walls.

2. In a bus structure, a plurality of longitudinally extending walls, a bus having a phase conductor extending along each wall longitudinally thereof, a line comprising a line conductor extending transversely along each wall, said line conductors lying in substantially the same transverse plane, a switch in each line conductor supported at the side of said walls, said walls with their correlated conductors and switches being spaced apart to provide free working room for an attendant between said walls.

3. In a structure of the class described, a plurality of longitudinally extending walls, a bus having phase conductors extending longitudinally one along each wall, a line comprising a line conductor for each phase extending along each wall in substantially a common transverse plane, a circuit breaker for each line conductor supported on the sides of said walls, a horizontal floor disposed above the bus, and circuit breaker operating mechanism extending transversely of the longitudinal walls for operating the circuit breakers of each phase simultaneously.

4. In a structure of the class described, a plurality of longitudinally extending walls, a bus having a phase conductor extending longitudinally along each wall, a line comprising a line conductor for each wall extending along each wall in a substantially common transverse plane, and transverse partitions on the sides of said longitudinal walls, lying on each side of the line conductor.

5. In a bus structure, a plurality of longitudinally extending walls, a bus having a bus conductor extending longitudinally along each wall, a plurality of lines comprising each a line conductor extending along each wall in substantially a transverse plane, vertical partitions along the sides of the walls forming cells, circuit breakers for each line conductor disposed in said cells, a horizontal mechanism floor above said longitudinal walls, and mechanism for operating the circuit breakers of a given line in unison disposed on said mechanism floor.

6. In a structure of the class described, a mechanism floor, a cable floor, a plurality of longitudinally extending vertical walls joining said floors, incoming lines formed in cables fanned out on said cable floor, said lines having conductors, one for each wall extending vertically along the walls and making connection with the bus conductors, vertical partitions lying between corresponding conductors of each line, circuit breakers for the conductors of

each line and operating mechanism for the circuit breakers of a given line, said operating mechanism being disposed on the mechanism floor.

- 5 7. In a structure of the class described, a plurality of vertical longitudinally extending walls, a bus having a bus conductor extending longitudinally along each wall, a plurality of lines having line conductors extending in transverse vertical planes along each wall, vertical transverse partitions along each wall separating the line conductors, switches connected in said line conductors, common operating mechanism disposed above the bus, a horizontal floor uniting the top of said longitudinal vertical walls and supporting said operating mechanism, and a horizontal floor member for each of said longitudinal vertical walls for supporting said line switches.

8. In combination, a plurality of longitudinal walls, a bus comprising phase conductors extending longitudinally of said walls, lines having phase conductors extending transversely along said longitudinal walls to make connection with the bus phase conductors, switches for each phase conductor of each line, common means for operating the switches of each line, a current limiting device connected in series with the line phase conductors on each line, transverse walls and partitions cooperating with the longitudinal walls for forming cells on each of said longitudinal walls for housing the switches and the current limiting devices.

9. In a structure of the class described, a series of longitudinal vertical walls, a horizontal upper wall uniting the tops of said vertical walls, switch operating mechanism mounted on said upper horizontal wall, an intermediate horizontal wall and a lower horizontal wall cooperating with said vertical longitudinal walls to form a series of galleries, a bus structure comprising a bus phase conductor disposed in the uppermost galleries, a line comprising a cable lying below the lower floor and having line phase conductors entering the galleries and extending vertically therethrough to the bus phase conductors, each phase conductor being disposed vertically along the side of the adjacent longitudinal wall.

10. In a structure of the class described, a series of longitudinal vertical walls, a horizontal upper wall uniting the tops of said vertical walls, switch operating mechanism mounted on said upper horizontal wall, an intermediate horizontal wall and a lower horizontal wall cooperating with said vertical longitudinal walls to form a series of galleries, a bus structure comprising a bus phase conductor disposed in each of the upper galleries, a line comprising a cable lying below the lower floor and having line phase conductors entering the galleries and ex-

tending vertically therethrough to the bus phase conductors, each line phase conductor being disposed vertically along the side of the adjacent longitudinal wall, switches connected in said line phase conductors, said switches being disposed in galleries lying on the same horizontal level, said operating mechanism being adapted to operate the switches for each line in unison, and current limiting devices for said line comprising a current limiting device connected in series in each line phase conductor, said current limiting devices being disposed in galleries on a common horizontal level.

11. In a structure of the class described, a series of longitudinal vertical walls, a horizontal upper wall uniting the tops of said vertical walls, switch operating mechanism mounted on said upper horizontal wall, an intermediate horizontal wall and a lower horizontal wall cooperating with said vertical longitudinal walls to form a series of galleries, a bus structure comprising bus phase conductors disposed in the upper galleries, a line comprising a cable lying below the lower floor and having line phase conductors entering the galleries and extending vertically therethrough to the bus phase conductors, each line phase conductor being disposed vertically along the side of the adjacent longitudinal wall, switches connected in said line phase conductors, said switches being disposed in galleries lying on the same horizontal level, said operating mechanism being adapted to operate the switches for each line in unison, current limiting devices for said line comprising a current limiting device connected in series in each line phase conductor, said current limiting devices being disposed in galleries on a common horizontal level, and vertical transverse partitions forming cells for housing each individual circuit breaker and each individual current limiting device.

12. In a structure of the class described, an upper floor, an intermediate floor and a lower floor, vertical longitudinal walls dividing said floors into galleries, a bus comprising bus phase conductors, one conductor extending longitudinally along each of said vertical walls in each of said galleries, vertical transverse partitions forming cells along corresponding sides of said longitudinal walls and lines connected to the bus, each line having line phase conductors passing through the cells vertically into connection with the corresponding bus phase conductor.

13. In a structure of the class described, an upper floor, an intermediate floor and a lower floor, vertical longitudinal walls dividing said floors into tiers of galleries, a bus comprising bus phase conductors, one conductor extending longitudinally along one side of each of said galleries, vertical

transverse partitions forming cells along corresponding sides of said longitudinal walls and lines connected to the bus, each line having line phase conductors passing through the cells vertically into connection with the corresponding bus phase conductor, line switches arranged in the cells on the upper tier of galleries and reactors arranged in the cells of the lower tier of galleries.

14. In a structure of the class described, an upper floor, an intermediate floor and a lower floor, vertical longitudinal walls dividing said floors into galleries, said galleries lying in tiers, a bus comprising bus phase conductors, one conductor extending longitudinally along one side of each of said galleries, vertical transverse partitions forming cells along corresponding sides of said longitudinal walls and lines having line phase conductors extending from below the lower floor to the bus phase conductor, each line having line phase conductors passing through the cells vertically into connection with the corresponding bus phase conductors, line switches arranged in the cells on the upper tier of galleries and reactors arranged in the cells of the lower tier of galleries, and switch operating mechanism disposed above the upper floor, each operating mechanism having means for actuating the switches for each phase of a given line.

15. In combination, a plurality of vertical longitudinally extending walls, a plurality of horizontal longitudinally extending walls comprising an upper wall, an intermediate wall and a lower wall, these longitudinal walls forming longitudinal galleries arranged in groups, vertical transverse partitions at one side of each longitudinal vertical wall for forming cells, cables lying below the lower floor, said cables being fanned out and having phase conductors extending upward through superposed cells vertically, a bus comprising bus phase conductors extending along the longitudinal vertical walls and passing through said vertical partitions on the upper tier of galleries, circuit breakers mounted in cells in the upper group of galleries, current limiting devices mounted in cells on the lower tier of galleries, the line phase conductors being in series with said circuit breakers and said current limiting devices.

16. In combination, a plurality of vertical longitudinally extending walls, a plurality of horizontal longitudinally extending walls comprising an upper wall, an intermediate wall and a lower wall, these longitudinal walls forming longitudinal galleries, arranged in groups, vertical transverse partitions at one side of each longitudinal vertical wall for forming cells, cables lying below the lower floor, said cables being fanned out and having phase

conductors extending upward through superposed cells vertically, a bus comprising bus phase conductors extending along the longitudinal vertical walls and passing through said vertical partitions on the upper tier of galleries, circuit breakers mounted in cells in the upper tier of galleries, current limiting devices mounted in cells on the lower tier of galleries, the phase line conductors being in series with said circuit breakers and said current limiting devices, and circuit breaker operating mechanism disposed above the uppermost floor for actuating the circuit breakers for each line in unison.

17. In a structure of the class described, three vertical longitudinal walls, a bus comprising three longitudinal phase conductors, one for each wall, said conductors extending longitudinally of the walls, transverse partitions forming cells on corresponding sides of each longitudinal vertical wall, conductors extending from said bus phase conductors and lying in each of said cells, said walls being spaced apart sufficiently to permit free room for a workman between the cells of each phase.

18. In combination, a plurality of longitudinal vertical walls, a bus comprising phase conductors lying on corresponding sides of each wall, vertical transverse partitions disposed on the corresponding sides of said longitudinal vertical walls, circuit breakers disposed in said cells, conductors connecting said bus phase conductors and said circuit breakers, operating mechanism disposed above the cells for the three phases, and operating rods extending from the mechanism to the circuit breakers.

19. In combination, a bus comprising bus phase conductors extending longitudinally and defining longitudinal planes, lines each comprising a plurality of phase conductors disposed in said planes, the phase conductors of each individual line lying in a substantially common transverse plane, said longitudinal planes being separated a sufficient distance apart to provide free working room for an attendant.

20. In combination, a bus comprising bus phase conductors extending longitudinally and defining longitudinal planes, lines each comprising a plurality of phase conductors disposed in said planes, the phase conductors of each individual line lying in a substantially common transverse plane, said longitudinal planes being separated a sufficient distance apart to provide free working room for an attendant, and longitudinal walls separating the phase conductors of the busses and the lines longitudinally, and transverse walls for separating the lines from each other in the same longitudinal plane.

21. In combination, a bus comprising bus

- phase conductors spaced apart and lying in separate vertical longitudinally extending planes, lines comprising phase conductors lying in the same vertical longitudinally 5 extending planes, the phase conductors of each line lying in substantially a common transverse vertical plane intersecting said longitudinal vertical planes, said bus phase conductors and their concomitant parts being spaced far enough apart to provide ample safety and to provide free working room for an attendant between phases, vertical longitudinally extending walls for separating the phases from each other, transverse partitions along said walls and horizontal longitudinal walls forming cells enclosing portions of the line phase conductors and the bus phase conductors, said cells being arranged in tiers on different levels, and apparatus connected in the line phase conductors disposed on the same level.
22. In a bus structure, a plurality of longitudinal walls, bus No. 1 having bus conductors disposed on homologous sides of said 25 walls, bus No. 2 having a bus conductor of the same phase disposed on the opposite sides of each of said walls respectively, said walls and conductors being spaced apart to provide free working room for an attendant 30 between phases.
23. In a structure of the class described, a plurality of longitudinally extending vertical walls, a bus structure comprising a phase conductor of the same phase on opposite sides of each wall respectively, lines adapted to be connected to the bus phase conductors, each line having line phase conductors lying on homologous sides of each of said longitudinal walls for connection 35 to the adjacent bus phase conductors.
24. In combination, three vertical longitudinal walls, each wall devoted to an individual phase, a bus structure comprising a phase conductor for each phase lying on 40 one side of each of said walls and another bus phase conductor lying on the other side of each of said longitudinal vertical walls, horizontal and vertical partitions at right angles to said longitudinal walls defining 45 groups of cells on each side of said longitudinal walls and conductors extending vertically along said longitudinal walls passing through corresponding groups of cells.
25. In combination, three vertical longitudinal walls, each wall devoted to an individual phase, a bus structure comprising a phase conductor for each phase lying on 50 one side of each of said walls and another bus phase conductor lying on the other side of each of said longitudinal vertical walls, horizontal and vertical partitions at right angles to said longitudinal walls defining 55 groups of cells on each side of said longitudinal walls and conductors extending vertically along said longitudinal walls passing 60 through corresponding groups of cells.
26. In combination, three vertical longitudinally extending walls, one devoted to each phase, a bus structure comprising phase conductors lying on opposite sides of each longitudinally extending wall, the conductors of each wall being of the same phase, a series of vertical transverse partitions 65 on each side of each wall, and horizontal partitions on each side of each wall defining vertically arranged groups of cells on each side of each wall, conductors connected to said bus phase conductors extending vertically through a group of cells, a circuit breaker in corresponding ones of each of said groups of cells, and overhead operating mechanism for actuating in unison corresponding circuit breakers of each phase.
27. In combination, a plurality of longitudinally extending vertical walls, bus conductors lying on opposite sides of each longitudinal wall and extending longitudinally thereof for each wall, vertical and horizontal 70 transverse partitions on each side of each wall for defining vertically disposed groups of cells on each side of each wall, line phase conductors for connected lines disposed in corresponding vertical groups of cells on homologous sides of each of the vertical walls, a circuit breaker for each phase conductor of a given line in one of said cells of a vertical group, and a current limiting device for each phase conductor of each line 75 in another one of the cells of a vertical group.
28. In combination, a plurality of longitudinally extending walls, bus conductors lying on opposite sides of each longitudinal wall and extending longitudinally thereof for each wall, vertical and horizontal partitions lying at substantially right angles to each other on each side of each wall for defining similar groups of cells on each side 80 of each wall, line phase conductors for connected lines disposed in corresponding groups of cells on homologous sides of each of the longitudinal walls, a circuit breaker for each phase conductor of a given line in one of said cells of a group, and a current limiting device for each phase conductor of each line in another one of the cells of said 85 group, and common mechanism for operating each of the circuit breakers of a given line.
29. In combination a vertical side wall, a longitudinally extending bus phase conductor extending longitudinally along one side of said wall, a circuit breaker lying 90 on one side of the wall, a line conductor extending from the bus phase conductor and being connected to said circuit breaker, said bus phase conductor extending transversely on the side of the wall, an overhead operat-

ing mechanism disposed above the wall, said mechanism having means extending down to the circuit breaker for operating the same.

30. In combination, a longitudinally extending wall, a bus phase conductor extending longitudinally along one side of said wall, a circuit breaker lying on one side of the wall, a line conductor extending from the bus phase conductor and being connected to said circuit breaker, said line phase conductor extending transversely on the same side of the wall, an overhead operating mechanism disposed above the top of the wall, said mechanism having means extending down to the circuit breaker for operating the same, and a disconnect for one side of the circuit breaker operated by the same overhead operating mechanism after the operation of the circuit breaker.

31. In combination, a longitudinally extending wall, a bus phase conductor lying lengthwise along one side of said wall, a line conductor extending from the bus phase conductor transversely on the same side of said wall, a current limiting device connected in series in said line conductor, a circuit breaker connected in series in said line conductor between the current limiting device and said bus phase conductor, a remote operating mechanism for operating the circuit breaker, and disconnects for each terminal of the circuit breaker, said disconnects being actuated by the operating mechanism when it opens the circuit breaker.

32. In combination, a longitudinal wall, a bus phase conductor extending longitudinally along one side of said wall, a circuit breaker lying on one side of the wall, a line conductor extending from the bus phase conductor and being connected to said circuit breaker, and said bus phase conductor, a remote operating mechanism for operating the circuit breaker, and disconnects for each terminal of the circuit breaker, said disconnects being actuated by the operating mechanism when it opens the circuit breaker, and a grounding wire for grounding the terminals of the circuit breaker when the disconnects are opened.

33. In combination, a longitudinally extending wall, a bus phase conductor mounted lengthwise of said wall, a line conductor extending transversely from the bus phase conductor, a circuit breaker connected in said line conductor, a remote operating mechanism for the circuit breaker having means extending to said circuit breaker for operating the same, disconnects on each side of the circuit breaker, and operating means for the disconnects extending through the longitudinal wall.

34. In combination, a longitudinally extending wall, a bus phase conductor lying lengthwise of said wall, a line conductor

extending from the bus phase conductor and being disposed transversely on the same side of the wall, a circuit breaker connected in said line conductor, a remotely actuated operating mechanism for operating said circuit breaker, disconnects lying on the same side of the wall and being adapted to disconnect the terminals of the circuit breaker, grounded contacts for the disconnects, a grounding conductor for said contacts extending through said wall, and connecting means between the operating mechanism and the circuit breaker, and separate connecting means between the operating mechanism and the disconnects.

35. In combination, a longitudinally extending wall, a bus phase conductor lying lengthwise along one side of said wall, a line conductor connected to said bus phase conductor and disposed substantially transversely at the same side of said wall, a circuit breaker connected in said line, a reactor also connected in said line, a remotely actuated operating mechanism, said mechanism having means reaching across the wall for operating the circuit breaker, and disconnects on the noncontiguous terminals of the circuit breaker and reactor, said circuit breaker and said disconnects being actuated by said operating mechanism.

36. In combination, a longitudinally extending wall, a bus phase conductor disposed horizontally along one side of the wall, partition walls at right angles to each other forming cells on said side of the wall, said cells being arranged in groups, a line conductor extending from the bus phase conductor through one of said groups, a circuit breaker and a current limiting device connected in series in said line conductor, and being disposed in separate cells in said group, disconnects in said line conductor between the bus and the circuit breaker and beyond the current limiting device, and operating means for operating the disconnects in unison.

37. In a switch house, a main bus extending a substantial distance lengthwise, said bus comprising phase conductors spaced apart a sufficient distance to provide free working room between phases and a plurality of line busses comprising corresponding phase conductors, each line bus phase conductor extending a limited distance longitudinally, said line bus phase conductors each lying in substantially the same plane as the corresponding main bus phase conductor.

38. In combination, a switch house, a main bus extending substantially the full length of said house, said bus comprising bus phase conductors spaced apart a sufficient distance to provide free working room between said phases, a plurality of line busses comprising corresponding phase con-

- ductors each line bus phase conductor extending parallel to the main bus conductors a limited distance, said line bus phase conductors each lying in common planes with the main bus phase conductors, and tie lines between the main bus phase conductors and the line bus phase conductors, said tie lines also lying in substantially said common planes.
39. In a switch house, a main bus extending a substantial distance longitudinally, said bus comprising bus phase conductors spaced apart a sufficient distance to provide free working room between phases, substantially non-conducting walls lying between phases, and a plurality of line busses comprising each line bus phase conductors extending parallel to the main conductors a limited distance, said line bus phase conductors each lying in substantially the same plane as the corresponding main bus phase conductor.
40. In a switch house, a main bus extending a substantial distance longitudinally, said bus comprising bus phase conductors spaced apart a sufficient distance to provide free room for workmen to pass between the phases, a plurality of line busses comprising each line bus phase conductors extending parallel to the main bus conductors a limited distance, said line bus phase conductors each lying in substantially a common plane with the corresponding main bus phase conductor, and substantially non-conducting barriers forming longitudinal channels for housing the main bus phase conductors and the line bus phase conductors.
41. In a switch house, a main bus extending a substantial distance longitudinally, said bus comprising bus phase conductors spaced apart a sufficient distance to provide free room for workmen to pass between the phases, a plurality of line busses comprising each line bus phase conductors extending a limited distance parallel to the main bus conductors, said line bus phase conductors each lying in substantially the same plane as the corresponding main bus phase conductor, and substantially nonconducting barriers forming longitudinal channels for housing the main bus phase conductors and the line bus phase conductors, tie lines between the main bus conductors and the line bus conductors and cells extending between said channels for housing said tie lines.
42. In a switch house, a main bus extending a substantial distance longitudinally, said bus comprising bus phase conductors spaced apart a sufficient distance to provide working room for an attendant between phases, a plurality of line busses comprising line bus phase conductors extending parallel to the main bus conductors a limited distance, each line bus conductor and its main bus conductor lying in substantially the same plane, substantially non-conducting walls forming longitudinal channels for said main bus conductors and for said line bus conductors, substantially nonconducting walls forming cells arranged in groups along said bus conductors of each phase, tie conductors between the main bus conductors and the line bus conductors for each phase, said ties lying in some of said cells.
43. In a switch house, a main bus extending longitudinally of the switch house, said bus comprising bus phase conductors spaced apart a sufficient distance to provide working room for an attendant between phases, a plurality of line busses comprising line bus phase conductors extending a limited distance longitudinally, said each line bus conductor and its main bus conductor lying in substantially the same vertical plane, substantially non-conducting walls forming longitudinal channels for said main bus conductors and for said line bus conductors, substantially nonconducting walls forming cells arranged in vertical groups along said bus conductors of each phase, tie conductors between the main bus conductors and the line bus conductors for each phase, said ties lying in some of said cells, switches in said ties, said switches being disposed in said cells.
44. In a switch house, a main bus extending longitudinally of the switch house, said bus comprising bus phase conductors spaced apart a sufficient distance to provide working room for an attendant between phases, a plurality of line busses comprising line bus phase conductors extending a limited distance longitudinally, said each line bus conductor and its main bus conductor lying in substantially a common plane, substantially non-conducting walls forming longitudinal channels for said main bus conductors and for said line bus conductors, substantially non-conducting walls forming cells arranged in vertical groups along said bus conductors of each phase, tie conductors between the main bus conductors and the line bus conductors for each phase, said ties lying in some of said cells, switches in said ties, said switches being disposed in said cells, line conductors extending transversely through groups of said cells for each phase, circuit breakers for said lines disposed in a corresponding group of cells for each phase.
45. In a switch house, a longitudinally extending bus comprising bus phase conductors spaced apart a sufficient distance to provide working room for attendants between phases, line busses extending a short distance longitudinally, said line busses of each phase having bus phase conductors disposed in substantially the same plane as the corre-

sponding main bus conductors, substantially non-conducting walls forming longitudinal channels for the bus conductors of the main bus and of the line busses transversely disposed groups of cells lying in substantially the same planes as said bus conductors, tie conductors between the main bus conductors and the line bus conductors, said tie conductors having circuit breakers disposed in said cells, line conductors for each of the line bus conductors lying in substantially the same plane as said bus conductors, said line conductors extending transversely and having circuit breakers therein disposed in said cells, the tie and line circuit breakers being disposed on substantially the same level throughout the switch house.

46. In a switch house, a longitudinally extending bus comprising bus phase conductors spaced apart a sufficient distance to provide working room for attendants between phases, line busses extending a short distance longitudinally, said line busses having bus phase conductors disposed in substantially the same plane as the main bus conductors, substantially non-conducting walls forming longitudinal channels for the bus conductors of the main bus and of the line busses, transversely arranged groups of cells lying in substantially the same planes as said bus conductors, tie conductors between the main bus conductors and the line bus conductors, said tie conductors having circuit breakers disposed in said cells, line conductors for each of the line bus conductors lying in substantially the same planes as said bus conductors, said line bus conductors extending transversely and having circuit breakers therein disposed in said cells, the tie and line circuit breakers being disposed on substantially the same level throughout the switch house, current limiting devices in the line conductors for each phase, said current limiting devices being disposed in cells and all of the current limiting devices lying on substantially the same level.

47. In a switch house, a longitudinally extending bus comprising bus phase conductors spaced apart a sufficient distance to provide working room for attendants between phases, line busses extending a short distance longitudinally, said line busses having bus phase conductors disposed in substantially the same planes as the main bus conductors, substantially non-conducting walls forming longitudinal channels for the bus conductors of the main bus and of the line busses, transversely arranged groups of cells lying in substantially the same transverse planes as said bus conductors, tie conductors between the main bus conductors and the line bus conductors, said tie conductors having circuit breakers disposed in said cells, line conductors for each of the line bus conductors lying in sub-

stantially the same planes as said bus conductors, said line bus conductors extending transversely and having circuit breakers disposed in said cells, the tie and line circuit breakers being disposed on substantially the same level throughout the switch house, current limiting devices in the line conductors for each phase, said current limiting devices being disposed in the cells and all of the current limiting devices lying on substantially the same level, and disconnects for disconnecting that portion of the line conductors which contain the circuit breakers and the said disconnects also lying in substantially the same planes as said bus conductors and being disposed in cells.

48. In a switch house, three vertical longitudinal walls, an overhead horizontal floor, longitudinally extending bus conductors lying on each side of said walls, circuit breakers also lying on each side of said walls, vertical and horizontal partitions forming cells on each side of each of said walls, lines having conductors disposed substantially vertically on each side of said walls and passing through said cells and connected through said circuit breakers, and overhead operating mechanism for the circuit breakers for operating the circuit breakers for each phase of a line in unison, said mechanism being disposed on said floor.

49. In a switch house, a plurality of bays, a main bus having phase conductors spaced apart to provide free working room for an attendant between phases, said bus extending longitudinally through a plurality of bays, a line bus for each bay, said line bus comprising line bus conductors lying substantially parallel to and above the main bus conductors, and walls forming longitudinal channels for said bus conductors, said channels having transverse partitions mounting insulators for supporting said bus conductors.

50. In a switch house, a plurality of bays, a main bus having phase conductors spaced apart to provide free working room for an attendant between phases, said bus extending longitudinally through a plurality of bays, a line bus for each bay, said line bus comprising line bus conductors lying substantially parallel to and above the main bus conductors, and walls forming longitudinal channels for said bus conductors, said channels having transverse partitions for supporting said bus conductors, a horizontal floor between said channels and circuit breakers for making connection to said line bus conductors disposed on said floor between said bus conductors.

51. In a switch house, a plurality of bays, a main bus having phase conductors spaced apart to provide free working room for an attendant between phases, said bus extend-

ing longitudinally through a plurality of bays, a line bus for each bay, said line bus comprising line bus conductors lying substantially parallel to and above the main bus conductors, and walls forming longitudinal channels for said bus conductors, said channels having transverse partitions for supporting said bus conductors, a horizontal floor between said channels and circuit breakers for making connection to said line bus conductors disposed on said floor between said bus conductors, a floor below said main bus conductors and current limiting devices on said latter floor connected in series with said circuit breakers.

52. In a switch house, a plurality of bays, a main bus having phase conductors spaced apart to provide free working room for an attendant between phases, said bus extending longitudinally through a plurality of bays, a line bus for each bay, said line bus comprising line bus conductors lying substantially parallel to and above the main bus conductors, and walls forming longitudinal channels for said bus conductors, said channels having transverse partitions for supporting said bus conductors, a horizontal floor between said channels and circuit breakers for making connection to said line bus conductors disposed on said floor between said bus conductors, a floor above the line bus conductors, and overhead operating mechanism for said circuit breakers disposed on said latter floor.

53. In a switch house, a plurality of bays, a longitudinally extending vertical wall passing through a plurality of bays, a main bus conductor extending along one side of said wall and spaced therefrom, a line bus conductor extending along said wall through one bay, longitudinal channels for housing said bus conductors, an intermediate horizontal floor between said busses, circuit breakers mounted on said latter floor, and vertically extending conductors supported on said longitudinal vertical wall, said latter conductors being connected in series with said circuit breakers.

54. In a switch house, a plurality of bays, a longitudinal vertical wall extending through a plurality of bays, a main bus conductor extending along one side of said wall and spaced therefrom, a line bus conductor extending along said wall throughout one bay, longitudinal channels for housing said bus conductor, an intermediate horizontal floor between said bus conductors, circuit breakers mounted on said floor, vertically extending conductors supported on said longitudinal vertical wall, said conductors being connected in series with said circuit breakers, an overhead wall forming a floor above said line bus conductors, and operating mechanism for the circuit breakers disposed on said overhead wall.

55. In a switch house, a plurality of bays, a longitudinal vertical wall extending through a plurality of bays, a main bus conductor extending along one side of said wall and being spaced therefrom, a line bus conductor extending through one bay along said wall, longitudinal channels for housing said bus conductors, an intermediate horizontal floor between said bus conductors, circuit breakers mounted on said floor, a lower horizontal wall, current limiting devices mounted on said lower wall, and conductors supported on said longitudinal vertical walls extending vertically and being connected in series with said circuit breakers and said reactors.

56. In a switch house, a plurality of bays, a longitudinal vertical wall extending through a plurality of bays, a main bus conductor spaced from and extending along one side of said wall, a line bus conductor extending along said wall through one bay, longitudinal channels formed of non-conducting material for housing said bus conductors, an intermediate horizontal floor between said bus conductors, circuit breakers mounted on said floor, vertically extending conductors supported on said longitudinal vertical walls, said conductors being connected in series with said circuit breakers, and disconnects supported on the same side of said wall for disconnecting said circuit breaker from said vertically extending conductors.

57. In combination, an overhead floor, an intermediate floor and a ground floor, a longitudinally extending vertical wall between said floors, a line bus below the overhead floor extending longitudinally of said vertical wall, a vertically disposed conductor extending from said line bus along the side of said wall vertically through the intermediate and the ground floors, vertical barriers on each side of said conductor, a disconnect in series in said conductor, horizontal partitions forming in connection with said barrier a cell for housing said disconnect, a circuit breaker disposed between said vertical barriers and being housed in a cell and connected in series with said conductor, a longitudinally extending main bus mounted in a channel below the intermediate floor, said conductor extending between said channel and the vertical wall, a current limiting device resting on the lower floor, and a horizontal partition above said reactor for forming a cell for housing said current limiting device.

58. In combination, a longitudinal vertical wall, an upper wall, an intermediate wall and a lower wall forming three floors, a line bus extending along the horizontal vertical wall and lying below the upper floor, a main bus extending longitudinally of the longitudinal vertical wall lying below the

intermediate floor, a line conductor extending from the line bus vertically downward along the longitudinal vertical wall and passing through the intermediate and 5 lower floors, vertical and horizontal barriers extending laterally from the main vertical wall to form a series of vertically aligned cells.

59. In combination, a longitudinal vertical wall, an upper wall, an intermediate wall 10 and a lower wall forming three floors, a line bus extending along the horizontal vertical wall and lying below the upper floor, a main bus extending longitudinally of the longitudinal vertical wall lying below the intermediate floor, a line conductor extending 15 from the line bus vertically downward along the longitudinal vertical wall and passing through the intermediate and lower floors, vertical and horizontal barriers extending laterally from the main vertical wall to form 20 a series of vertically aligned cells, a circuit breaker disposed in a cell immediately above the intermediate floor, and a current limiting device disposed in a cell immediately 25 above the lower floor, said circuit breaker and current limiting device being connected in series in said line conductor.

60. In a structure of the class described, a longitudinally extending vertical wall, 30 main busses supported longitudinally along said wall on each side thereof, line busses extending longitudinally along each side of said wall, conductors and switch mechanism disposed on each side of the wall between 35 said busses and adapted to connect either line bus to either main bus.

61. In combination, a longitudinal vertical wall, a transverse horizontal floor, main bus conductors, one lying on each side of 40 the vertical wall and below the horizontal floor, line bus conductors lying on each side of the vertical wall a substantial distance above the horizontal floor, and switch mechanism supported on the horizontal floor for 45 connecting the line busses and the main busses.

62. In combination, a switch house, three longitudinal vertical walls, an overhead floor joining said walls, longitudinally extending 50 busses having conductors mounted on corresponding sides of said walls, vertically disposed line conductors extending from said bus conductors along said walls, horizontal walls extending outward laterally 55 from said vertical walls, circuit breakers in said line conductors mounted on said horizontal walls, vertical partitions extending from said overhead floor downwardly to house said line conductors and circuit breakers, operating members for said circuit breakers extending down through the 60 overhead floor, common transverse connecting means connecting said operating members, and actuating means for said connecting means.

63. In a switch house, a main longitudinal vertical wall, vertical and horizontal walls extending out from one side of the main wall and forming cells, a bus extending longitudinally through said extending vertical 70 walls, and a line extending vertically through said horizontally extending walls, and a circuit breaker for connecting said line to said bus, said circuit breaker being housed in one of said cells. 75

64. In a system of the class described, a generator Y connected and having a grounded neutral connection, a current limiting resistance in said grounded connection, a bus system connected to said generator, reactors in the connection between the generator and the bus system, said bus system comprising segregated phase conductors spaced apart sufficiently far to provide working space for an attendant between 80 phases, lines comprising cables fanned out to a spacing substantially the same as the bus phase conductors, and current limiting devices connected in the line conductors in 85 advance of the connection of the same to the bus conductors. 90

65. In combination, a longitudinal wall, a bus conductor of the same phase mounted on each side of said wall and extending longitudinally thereof, line conductors connected to said bus conductors and extending along said wall transversely of said bus conductors, line switches connected in 95 said line conductors and supported at the corresponding sides of said wall. 100

66. In combination, a longitudinal wall, a bus conductor of the same phase mounted on each side of said wall and extending longitudinally thereof, line conductors connected to said bus conductor and extending along said wall transversely of said bus conductors, line switches connected in said line conductors and supported at the corresponding sides of said wall, other walls extending longitudinally and forming with said longitudinal wall a gallery on each side of the first longitudinal wall. 110

67. In combination, a longitudinal wall, a bus conductor of the same phase mounted on each side of said wall and extending longitudinally thereof, line conductors connected to said bus conductor and extending along said wall transversely of said bus conductors, line switches connected in said line conductors and supported at the corresponding sides of said wall, and transverse partitions extending out laterally from said longitudinal wall for housing said line switches. 115

68. In combination, a longitudinal gallery having a floor and a side wall, a bus phase conductor extending longitudinally along said side wall, line conductors lying at said side wall and extending transversely with respect to said bus conductor, circuit break- 125 130

ers in said line conductors, said circuit breakers being of the same phase and being mounted in a row on the floor of the gallery adjacent the side wall.

- 5 69. In combination, a longitudinal gallery having a floor and a side wall, a bus phase conductor extending longitudinally along said side wall, line conductors lying at said side wall and extending transversely with
10 respect to said bus conductor, circuit breakers in said line conductors, said circuit breakers being of the same phase and being mounted in a row on the floor of the gallery adjacent the side wall, and trans-
15 verse partitions forming cells for housing said circuit breakers.

70. In combination, three longitudinal walls, each wall devoted to a phase, a bus comprising a bus phase conductor on one
20 side of each wall, another bus phase conductor lying on the other side of each wall, partitions at right angles to each other and to the longitudinal walls forming rows of cells on each side of each wall and phase
25 conductors connected to said bus conductors extending through a plurality of cells, on corresponding sides of said longitudinal walls, and switches connected in said conductors said switches lying in correspond-
30 ing ones of said cells for each longitudinal wall.

71. In combination, a longitudinal wall, a longitudinally extending bus phase conductor mounted along one side of said wall, a transversely disposed line conductor on
35 the side of the wall, a switch in said conductor, a remote operating mechanism and an operating rod extending through said wall for operating said switch.

40 72. In combination, a cell having top and bottom walls, side walls and a back wall, a circuit breaker and a disconnect disposed in said cell, the circuit breaker being mounted on the bottom wall and the disconnect
45 being mounted on the top wall, and common operating means for said circuit breaker and said disconnect.

73. A row of adjacent cells formed of a common back wall and common top wall
50 and a common bottom wall and intermediate partitions, a disconnect and a circuit breaker in each cell, common means for operating the circuit breaker and disconnect of each cell in proper sequence, and a common phase conductor having branches connected to all the circuit breakers of the row.

74. In combination, a series of longitudinal parallel walls, a series of transverse longitudinal walls defining a series of galleries, a bus structure comprising a bus phase conductor extending along the side wall of corresponding ones of a group of said galleries, said latter galleries having free working space between conductors, and
60 line conductors extending along the same

walls transversely of said bus conductors.

75. In a switch-house, a series of galleries defined by two groups of parallel longitudinal walls, bus conductors each individual to a gallery extending longitudinally there-
70 of, lines, each extending transversely through a plurality of galleries and circuit breakers for said lines housed in correspond-
ing ones of said galleries.

76. In a bus structure, a plurality of 75 longitudinal vertical walls, a plurality of longitudinal horizontal walls, said walls defining longitudinal galleries, a bus having a bus conductor extending along the side of the vertical walls in corresponding ones 80 of said galleries and connections to and from said bus conductors extending trans-
versely along the vertical walls and passing through a plurality of galleries and circuit
85 breakers in said connections, said circuit breakers being housed in corresponding ones of said galleries.

77. In combination, a bus comprising bus phase conductors spaced apart and lying in separate longitudinally extending planes, lines comprising phase conductors lying in the same longitudinally extending planes, the phase conductors of each line lying sub-
stantially in a common transverse plane intersecting said longitudinal planes, said bus phase conductors and their concomitant 90 parts being spaced far enough apart to provide ample safety and to provide free working room for an attendant between phases, longitudinally extending walls parallel to the first longitudinally extending planes for separating the phases from each other, transverse partitions along said walls and longitudinal walls at right angles to the first walls forming cells corresponding cells
95 enclosing portions of the line phase conductors and the bus phase conductors, said cells being arranged in similar groups on different levels, and switches connected in
100 said line phase conductors disposed in corresponding cells.

78. A bus support comprising a longitudi-
dinal channel formed of three walls of concrete, transverse walls of concrete dividing said channel into relatively short lengths, a bus conductor lying in said channel, said transverse walls having openings through which said bus conductor is threaded and bushing type insulators surrounding said conductor and being supported in said trans-
verse walls.

79. In a switch house, a bus, a plurality of lines, circuit breakers for connecting said lines to said bus, a disconnect switch between the bus and the circuit breaker of each line, said disconnect switches having grounding contacts, a grounding cable connected in multiple to said grounding contacts, a ground connection, and a switch in series between said grounding cable and
125 said ground connection.

80. In a system of the class described, one or more generators, a bus system comprising segregated bus phase conductors spaced apart from each other a distance invariably in excess of the distance required because of voltage, a plurality of lines comprising phase conductors connected to the bus phase conductors, current limiting devices in series with said line phase conductors, said line phase conductors on the bus side of the current limiting devices being invariably segregated by separation to substantially the same degree as the bus phase conductors.

81. In combination a plurality of longitudinal galleries, a longitudinal wall for each gallery, a bus comprising a bus phase conductor extending longitudinally along each wall, lines comprising line conductors extending transversely to the bus phase conductors and transversely along the corresponding walls, and protective and interrupting devices connected in each of said line conductors and disposed along the corresponding walls, the line conductors being insulated and converging to a cable beyond the protective and interrupting devices.

82. In a switch house, a plurality of bus phase conductors lying in longitudinal planes, lines comprising line phase conductors joining said bus phase conductors and lying in the same planes as the corresponding bus phase conductors, and switching means in each line phase conductor said switching means lying in substantially the same plane as the corresponding line phase conductor, said line phase conductors departing from the corresponding planes and converging into cables only after passing through said switching means.

83. In a switch house, a plurality of longitudinal galleries, a bus comprising a bus phase conductor disposed in each gallery and extending longitudinally thereof, and a plurality of lines comprising phase conductors entering transversely the corresponding galleries and being disposed on the walls of the galleries in planes substantially at right angles to the longitudinal bus phase conductors.

84. In a switch house, a plurality of longitudinal galleries, a bus comprising bus phase conductors one for each gallery, said bus phase conductors extending longitudinally through said galleries, a plurality of lines comprising line phase conductors entering transversely the corresponding galleries and being connected to the corresponding bus phase conductors, and current limiting devices enclosed in the galleries, said current limiting devices being connected in the bus phase conductors before they emerge from the galleries.

85. In a switch house, a plurality of longitudinal galleries, a bus comprising bus phase conductors one for each gallery, said

bus phase conductors extending longitudinally through said galleries, a plurality of lines comprising line phase conductors entering transversely the corresponding galleries and being connected to the corresponding bus phase conductors, and current limiting devices enclosed in the galleries, said current limiting devices being connected in the bus phase conductors before they emerge from the galleries and cables connected to the bus phase conductors after they emerge from the galleries.

86. In a switch house, a plurality of longitudinal galleries, a bus comprising bus phase conductors each enclosed in one of said galleries and extending longitudinally thereof, a plurality of lines comprising line phase conductors entering transversely the corresponding galleries and being connected to the bus phase conductors, current limiting devices enclosed in the galleries, said current limiting devices being connected in the bus phase conductors before they emerge from the galleries, line switches in said line phase conductors, said switches being disposed in said galleries between said bus phase conductors and said current limiting devices, and common operating mechanism for operating the switches of a given line in unison.

87. In a switch house, a plurality of longitudinal galleries, a bus comprising a bus phase conductor for each gallery, said bus phase conductors being disposed in and extending longitudinally in said galleries, a plurality of lines comprising line phase conductors entering transversely the corresponding galleries, current limiting devices enclosed in the galleries, said current limiting devices being connected in the line phase conductors before they emerge from the galleries, line switches in said line phase conductors connected between said bus phase conductors and said current limiting devices, a longitudinally extending gallery for operating mechanism and common operating mechanism for operating the switches of a line in unison, said operating mechanism having operating rods reaching across the galleries of the bus phase conductors.

88. In a switch house, a plurality of longitudinal galleries, a bus comprising a bus phase conductor enclosed in and extending longitudinally in each gallery, a plurality of lines having line phase conductors connected to the bus phase conductors and emerging from said galleries, line switches connected in said line phase conductors in said galleries and common operating mechanism for operating the switches of a line in unison, said operating mechanism having means reaching across said longitudinal galleries for operating the line switches.

89. In a structure of the class described, a series of longitudinal galleries each of a

cross sectional size large enough to provide free working room therein for an attendant, a bus comprising phase conductors, each phase conductor being disposed in a corresponding gallery and thereby segregated by spaces in excess of the insulation requirements, lines connected to the bus, each line comprising line phase conductors, said line phase conductors entering the corresponding galleries and being therein connected to the corresponding bus phase conductors and apparatus for switching protective and measuring purposes individual to each line phase conductor all housed in the corresponding galleries and thereby segregated to substantially the same degree as the bus phase conductors.

90. In a system of the class described one or more generators, a bus system comprising segregated bus phase conductors spaced apart a distance invariably in excess of the distance required because of voltage, a plurality of lines comprising phase conductors connected to the bus phase conductors, current limiting devices in series with said line phase conductors at a point adjacent the connection of line and bus phase conductors, said line phase conductors on the bus side of the current limiting devices being segregated to substantially the same degree as the bus phase conductors and a longitudinal gallery for each phase, enclosing the corresponding segregated bus phase conductors and the corresponding current limiting devices connected thereto.

91. In a system of the class described, one or more generators, a bus system comprising segregated bus phase conductors spaced apart a distance invariably in excess of the distance required because of voltage, a plurality of lines comprising phase conductors connected to the bus phase conductors, current limiting devices in series with said line phase conductors at a point adjacent the connection of line and bus phase conductors, said line phase conductors on the bus side of the current limiting devices being segregated to substantially the same degree as the bus phase conductors, circuit breakers for switching the lines in series with the line phase conductors and a longitudinal gallery for each phase enclosing the corresponding segregated bus phase conductors and the corresponding current limiting devices and circuit breakers connected thereto, said line conductors, current limiting devices, and switches being disposed in planes transverse to the longitudinal galleries and being disposed adjacent the walls of the galleries.

92. In combination a longitudinally extending gallery having walls, a bus phase conductor lying lengthwise in the gallery along one wall of the gallery, a line conductor extending transversely from the bus

phase conductor along the wall of said gallery, a reactor in the gallery connected in series in said line conductor before it emerges from the gallery, a circuit breaker connected in said line phase conductor within said gallery, a remote operating mechanism for operating the circuit breaker, said operating mechanism lying outside of the gallery and having an operating rod extending into the gallery for operating the circuit breaker.

93. In combination a longitudinally extending gallery having walls, a bus phase conductor lying lengthwise in the gallery along one wall of the gallery, a line conductor extending transversely from the bus phase conductor along the wall of said gallery, a reactor in the gallery connected in series in said line conductor before it emerges from the gallery, a circuit breaker connected in said line phase conductor within said gallery, a remote operating mechanism for operating the circuit breaker, said operating mechanism lying outside of the gallery and having an operating rod extending into the gallery for operating the circuit breaker, and a disconnect for the circuit breaker, said disconnect being actuated by the operating mechanism which operates the circuit breaker.

94. In combination a longitudinal vertical wall, other longitudinal walls co-operating with said first wall to form a longitudinal gallery, a bus phase conductor disposed longitudinally in said gallery along one wall, a line phase conductor extending into said gallery transversely to said bus phase conductor, switching and protective apparatus connected in series in said line phase conductor and disposed near the walls of the gallery in a transverse plane and leaving free working space in the gallery for an attendant.

95. In combination longitudinal walls defining a gallery, a bus phase conductor mounted longitudinally along a wall of the gallery, a transversely disposed line phase conductor, a circuit breaker in series in the line phase conductor, partitions extending transversely from the longitudinal walls for forming cells, said bus and line phase conductors and said circuit breakers being disposed in said cells and thereby leaving the central part of the gallery clear for an attendant.

96. In combination longitudinal walls defining a gallery, a bus phase conductor mounted longitudinally along a wall of said gallery, a transversely disposed line phase conductor entering said gallery and being connected to said bus phase conductor, a circuit breaker in said line phase conductor disposed adjacent a side wall of said gallery, a cell formed on the wall adjacent the circuit breaker to house the same, operating mechanism for operating the circuit breaker

disposed on the outside of the gallery and an operating rod extending through a wall of the gallery and connecting the operating mechanism of the circuit breaker.

5. 97. In combination longitudinal walls defining a gallery, a bus phase conductor mounted longitudinally along a wall of the gallery, a transversely disposed line phase conductor lying in a transverse plane, a circuit breaker and a disconnect in series in said line phase conductor, operating mechanism disposed outside of the gallery and mechanically operated means extending from the operating mechanism through a wall of the gallery to the circuit breaker and the disconnect for operating the same.

98. In combination, a bus comprising a plurality of segregated bus phase conductors,

a plurality of cables leading to said bus, each cable having phase conductors fanned out to the spacing of the bus phase conductors and connected thereto, switching and protective apparatus connected in series in each of the fanned-out phase conductors and disposed adjacent the union of the corresponding cable phase conductors and the bus phase conductors, the corresponding switching and protective apparatus for each phase and that portion of the fanned-out phase conductor lying between such switching and protective apparatus and the bus phase conductors being segregated to substantially the same degree as the bus phase conductors.

In witness whereof, I hereunto subscribe my name this 3rd day of April, 1922.

BERTRAND G. JAMIESON.
